UNITED STATES PATENT OFFICE.

HENRY F. G. FUCHS, OF JERSEY CITY, NEW JERSEY.

DESIGN FOR A BADGE.

SPECIFICATION forming part of Design No. 22,226, dated February 21, 1893.

Application filed December 17, 1892. Serial No. 455,537. Term of patent 7 years.

To all whom it may concern:

Be it known that I, HENRY F. G. FUCHS, a citizen of the United States, residing at Jersey City, in the county of Hudson and State 5 of New Jersey, have invented and produced a new and original Design for a Badge, to be used as a lapel ornament or for other suitable form of decoration, of which the following is a specification, reference being had to the accompanying drawings, forming part thereof, in which—

The leading feature of my design consists 15 of a spray of three leaves connected with a stem, in form of a shamrock, and each leaf having an outline of scallops uniform in dimensions and an interior composed of radial lines extending from the center of the leaf to 20 points between said scallops. The outline formed by the outer ends of the lines forming the interior of the leaf is wholly within the outline formed by the exterior edges of the scallops.

The drawings present a perspective view of 25 a badge embodying my design.

In the drawings A is the leaves and B the stem therefor. Each leaf A has a scalloped exterior inclosing edge C and an interior D, the latter being composed of closely arranged 30 radial lines extending from the center of the leaf to points between the said scallops. The scallops composing the edge C are uniform in size and in their relation to each other and their outer tips constitute an outline lying 35 beyond the outline formed by the outer ends of the aforesaid radial lines D.

What I claim is—

The design for a badge substantially as shown and described.

HENRY F. G. FUCHS.
